Kevin Prince(57) **CLAIM**

The ornamental design for a dunnage bag installation device, as shown and described.

DESCRIPTION

FIG. 1 is a perspective view of a dunnage bag installation device in an open configuration, showing our new design;
FIG. 2 is a front elevational view of FIG. 1;
FIG. 3 is a rear elevational view of FIG. 1;
FIG. 4 is a left-side elevational view of FIG. 1, the right-side elevational view being a mirror image thereof;
FIG. 5 is a top plan view of FIG. 1;

FIG. 6 is a bottom plan view of FIG. 1;
FIG. 7 is a perspective view in a closed configuration thereof;
FIG. 8 is a front elevational view of FIG. 7;

FIG. 9 is a rear elevational view of FIG. 7;
FIG. 10 is a left-side elevational view of FIG. 7, the right-side elevational view being a mirror image thereof;
FIG. 11 is an top plan view of FIG. 7; and,
FIG. 12 is a bottom plan view of FIG. 7.

The broken lines showing a dunnage bag in the figures depict environmental matter and form no part of the claimed design.
